[57] **CLAIM**

The ornamental design for a template for electrical box
placement, as shown and described.

DESCRIPTION

FIG. 1 is a top, front and right side perspective view of
a template for electrical box placement showing our
new design;

FIG. 2 is a top plan view;

FIG. 3 is a bottom plan view;

FIG. 4 is a left side elevational view; and

FIG. 5 is a rear elevational view thereof.

FIG. 1

FIG. 2

FIG. 3

FIG. 4

FIG. 5
